Inventor:

Arthur L. Stevens.

UNITED STATES PATENT OFFICE.

ARTHUR L. STEVENS, OF PHILADELPHIA, PENNSYLVANIA, ASSIGNOR OF ONE-HALF TO THE REMINGTON MACHINE COMPANY, OF WILMINGTON, DELAWARE.

PRINTING DEVICE.

SPECIFICATION forming part of Letters Patent No. 415,985, dated November 26, 1889.

Application filed May 20, 1889. Serial No. 311,438. (No model.)

To all whom it may concern:

Be it known that I, ARTHUR L. STEVENS, a citizen of the United States, residing at Philadelphia, in the State of Pennsylvania, have 5 invented a new and useful Printing Device, of which the following is a specification.

My invention relates to a device for printing a brand or number upon paper bags, and is designed to be attached to a paper-bag 10 machine and work simultaneously with it. It is designed more particularly to be used in connection with the paper-bag machine described by me in an application filed March 14, 1889, Serial No. 303,232; but it is equally 15 well adapted to other machines and for other purposes.

The object of my invention is to make a simple device that will comprise a type-roll and ink-fountain combined, that will insure 20 equal distribution of the ink, that will admit of a quick change of type and an adjustable impression, that will protect the ink from the atmosphere, and that will be self-contained and accessible, all its internal movements 25 being performed consequent upon the simple rotation of the fountain-roll. I attain these objects by the mechanism illustrated in the accompanying drawings, in which—

Figure 1 is a longitudinal section through 30 the roll. Fig. 2 is a transverse section on line F G. Fig. 3 is a transverse section on line C D, and shows also the position and relation of the fountain-roll with other rolls in a bag-machine. Fig. 4 is a transverse section on line A B, showing device for feeding ink. Fig. 5 is a detail view of one of the bearings and device for regulating the impression. Figs. 6 and 7 are views of the ink-distributing roll, and Fig. 8 is an illustration 35 of the class of work the device is designed to do.

Similar reference-signs refer to similar parts throughout the several views.

The fountain-roll 1 is made in two parts, 45 and secured together by screw-bolts 2 and keyed to shaft 6. The shaft 6 is supported in bearings 7 and 8, and has keyed to its end the disk 9. The disk 9 has a T-groove 10 in its face. The driving-gear 11 is clamped to

the face of the disk by the bolt 12 in the T- 50 groove. The end of the shaft is squared at 13. The cored chamber 3 in the roll 1 is for ink. At the center of the roll its diameter is reduced a little, forming an ink-distributing surface 4. A hole is drilled from the end in 55 such a position that it will cut through or be tangent with the surface 4, and has inserted in it the spindle 5. The metal is cut away a little at 14, leaving the top of spindle 5 exposed. Holes 42 are drilled through from the 60 spindle-chamber into the ink-chamber 3, from which the ink flows by centrifugal action due to the rotation of the roll. The spindle 5 thus forms a valve which closes the passage 65 for ink, but feeds it slowly, as used, by oscillating in its seat. This is accomplished by means of the fork 17, secured to the outer end of the spindle and spanning the fixed eccentric 16, which is formed on the end of the bearing 7. The ink is distributed over the 70 surface 4 by means of the roll 15. In the opposite side of the fountain-roll from the spindle 5 is the sliding type-block 18. On the end of bearing 8 is the adjustable sliding block 19, having a sleeve-extension terminating in an 75 eccentric 20. One side of the sliding block 19 is dovetailed with the bearing 8, and in the other side is inserted the screw 21, the block 19 being threaded and counterbored a short distance in at each side to allow the heads of 80 the screw to enter. The half of the hole for screw 21 that is in the bearing 8 is smooth without threads, and the heads of the screw bear against each side. By turning the screw the block 19 is caused to slide across the end 85 of the bearing 8, increasing or diminishing the eccentricity of the collar 20 with the shaft 6.

Centered on pin 22 in roll 1 is the fork or yoke 23, which spans the eccentric 20. On 90 one arm of the fork is the boss 24, which is drilled out to receive the shouldered pin 25. A slot or opening is made through the web of the roll 1 into the radial slot containing the type-block, and through this opening extends 95 the boss 24 and pin 25. The type-block is slotted to receive the pin which holds it in position. The pin 25 has a nut or head 26 and

a spring 27 forces the pin into the slot in the type. The type can be removed by pulling back the pin by means of the head 26. As the roll 1 revolves, the fork 23 will, by means of the eccentric 20, vibrate the pin 25 toward and from the center of the roll, thus alternately depressing the face of the type even with the depressed surface 4 when the type is opposite the inking-roll 15, as in Fig. 3, and raising it even with the outer surface when revolved to the opposite side or to the point where it is desired to impress the type against the paper.

Fig. 3 shows the relative position of the fountain-roll with other parts of a bag-machine in which the roll 28 is the impression-roll, or the roll against which the type is pressed, and has in this case a yielding surface at 29, where the impression is received. The bags are formed and delivered from between the rolls 28 and 30 and pass between rolls 28 and 1. Near the upper end of each bag is generally a brand or number denoting its size, as in Fig. 8. These rolls 1, 28, and 30 are geared together and make one revolution for each bag. To time the roll 1 so that the type will print at the desired place on the bag, the screw 12 is loosened, and as the bag is brought to the desired position the roll 1 is turned by means of the square head 13 so that the type will impress the desired place on bag. The bolt 12 is then tightened, clamping the gear to shaft, and as the gear 11 meshes with a corresponding gear on roll 28, it follows that the relative position of the rolls 1 and 28 remain fixed until it is desired to change them again by the means just described. The bearings for the roll 1 are supported upon stiff steel springs 31, bolted to the frame of the machine, the object being to insure firm contact between the surface of the rolls 1 and 28, at the same time allowing varying thicknesses of paper to pass between them. The ink-distributing roll 15 is carried on one end of the spindle 32, which has bearings in the hinged piece 33. This hinged piece is secured to the frame of the machine by means of the foot 34. The roll is forced upward against the type and ink-fountain by means of the spring 35. The spindle 32 is splined and has a worm 36 thereon. Engaging with this worm is the worm-wheel 37, secured to a stud 38, having an eccentric head 39. Fulcrumed to the hinged piece 33 is the forked bell-crank 40, which is actuated by the said eccentric and has a pin 41, projecting into a groove in the end of spindle 32. This arrangement gives a lateral movement to the ink-roll as it revolves, distributing the ink more uniformly than it would without this movement.

In operation the fountain is supplied with ink and the type set to register at the right point on the bag, and the machine started. The fountain-roll revolves once for each bag, and as the type approaches the roll 28 the fork 23, in revolving around the adjustable

eccentric collar 20, forces the type out against the roll 28 with a pressure depending upon the adjustiment of said eccentric by means of the thumb-screw 21. As the motion of the roll continues the type is withdrawn and brought even with the ink-distributing surface 4, and in this position passes the roll 15. At each revolution of the fountain the spindle 5 is oscillated by means of the fork 17 and eccentric 16, thus supplying ink to the roll 15. The roll 15 revolves by contact with the fountain-roll and has a lateral movement, as before described, for the purpose of distributing the ink uniformly.

All the movements required to perform the various functions and offices of the parts are secured by simple means, dependent upon the rotation of the roll 1, and the device is all self-contained, thus making it well adapted to be attached to any machine.

Having described my invention, what I claim as new, and desire to secure by Letters Patent, is—

1. In a printing device, the combination of an ink-fountain roll with a sliding type-block, said type being raised and depressed by a fork fulcrumed to said roll and revolving around an eccentric which is secured to a fixed bearing, substantially as described, and for the purpose set forth.

2. In a printing device for paper-bag machines, a fountain-roll having a depressed surface for the distribution of ink, a device to feed ink from the interior of said fountain-roll to the distributing-surface, consisting of an oscillating spindle inserted in said roll, with its surface tangent with said distributing-surface, and by its oscillations supplying ink through openings in the fountain-roll, in combination with an ink-distributing roll and type sliding in said fountain-roll, the face of said type being pushed out even with the outer surface of the fountain-roll and then depressed even with the said distributing-surface as it passes the ink-roll, substantially as described, and for the purpose set forth.

3. A printing attachment for paper-bag machines, comprising the fountain-roll 1, the inking-roll 15, the sliding type 18, the spindle-valve, and ink-feeder 5, the said spindle oscillating as the fountain revolves, thereby supplying ink to the roll 15, which distributes it over the depressed surface 4 of said fountain and the face of the type 18, the type 18 being pushed out once in each revolution of the fountain even with its outer surface, substantially as described, and for the purpose set forth.

4. A printing device for paper-bag machines, having an ink-fountain roll with a depressed surface and having openings communicating with the interior of said roll and the outside, said openings being closed by an oscillating spindle valve and feeder which is actuated by means of a fixed eccentric and a fork on the end of said spindle, a sliding type-block

which is alternately pushed out even with the outer surface of the roll and withdrawn even with the depressed surface for the purpose of receiving ink from the ink-roll and printing the same against the paper, and an ink-distributing roll, substantially as described.

5. In a printing device for paper-bag machines, the combination of a fountain-roll having an ink-feeding spindle and distributing roll, as described, with a sliding type-block actuated by means of a fork or yoke fulcrumed to said fountain-roll, and an eccentric fixed to one of the bearings of said roll.

6. In a printing device for paper-bag machines, the roll 1, having a depressed ink-distributing surface, such as 4, and an ink-feeding spindle 5, actuated by means of the fixed eccentric 16, said roll being provided with a sliding type-block 18, which is raised and lowered by means of the yoke 23 and the adjustable eccentric 20, in combination with an ink-distributing roll in contact with said depressed surface 4 and having a lateral motion imparted to it as it revolves, substantially as described.

7. In a printing attachment for paper-bag machines having a fountain-roll, such as 1, with depressed ink-distributing surface 4 and ink-feeding device, such as described, the combination of a sliding type-block 18 with the fork 23, which is connected to said type by the sliding pin 26, the adjustable eccentric 20, and the distributing-roll 15, all substantially as described, and for the purpose set forth.

8. In a printing attachment for paper-bag machines, the roll 1, having a depressed surface at 4, upon which ink is distributed by the roll 15, in combination with the type-block 18, the yoke 23, having pin 26 projecting into a slot in said type-block, and the yoke-actuating eccentric 20 on the end of the sliding block 19, said sliding block 19 being fitted to the end of one of the bearings for the said roll 1 and ca-

pable of adjustment by means of the thumb-screw 21, thereby increasing or diminishing 45 the eccentricity of said eccentric 20, substantially as described, and for the purpose specified.

9. A printing attachment for paper-bag machines, comprising the fountain-roll 1, having an oscillating spindle 5 to feed the ink, the sliding type 18, actuated by the yoke or fork 23 and adjustable eccentric 20, said eccentric being on a sliding piece fitted to the end of one of the bearings, said yoke being provided 55 with the pin 26 and spring 27 for the purpose specified, and the ink-distributing roll 15, substantially as described.

10. In a printing attachment for paper-bag machines, the combination of the fountain- 60 roll 1 and type 18 with the ink-roll having a worm 36 on its splined spindle 32, the said worm engaging with the worm-wheel 37, which actuates the bell-crank 40 by means of the eccentric 39, thereby vibrating the spindle and 65 roll laterally as it revolves in contact with said fountain-roll, substantially as described.

11. A printing attachment for paper-bag machines, comprising the fountain-roll 1, having the sliding type 18, and fork 23, actuated by 70 the eccentric 20 for the purpose specified, said fork being connected with said type by the pin 26, and the ink-feeding spindle 5, actuated by the fork 17 and eccentric 16, in combination with the ink-distributing roll 15, having on its 75 spindle a worm 36, engaging with the worm-wheel 37, the eccentric 39 being secured to said wheel and actuating the bell-crank 40, which is connected with the spindle 32, thereby vibrating said roll 15 laterally as it revolves 80 in contact with said fountain-roll.
